UNITED STATES PATENT OFFICE.

MORGAN L. ROGERS, OF SPRING, PENNSYLVANIA.

IMPROVEMENT IN CULTIVATORS.

Specification forming part of Letters Patent No. 26,618, dated December 27, 1859.

To all whom it may concern:

Be it known that I, MORGAN L. ROGERS, of Spring, in the county of Crawford and State of Pennsylvania, have invented a new and Improved Corn-Plow and Cultivator Combined; and I do hereby declare that the following is a full and exact description of the same, reference being had to the accompanying drawings and the letters of reference marked thereon.

Figure 1 represents my cultivator with all its parts adjusted in working order.

A B C are the several parts composing the frame. Of these A and B are of round iron and bent as shown in drawings, on which the blades of the plows 2 and 3 are bolted, as hereinafter described.

C is an iron bar, made flat along the portion E C, while to one end is a hook, w. The other is bent down like A and B, and to this bent portion another rod, N, is welded or bolted, and also the blade 7 8. Through the upper end of the rod N is an eye turned, and a stick or rung, separating the handles H I, passes through this eye. The front ends of A and B have holes punched through them, and are placed between two plates, E and D', through which holes and plates two bolts, with nuts and screws, pass. (See 4 5, Fig. 1.) This construction forms a hinge, by means of which A and B can be separated to any desired distance apart, while they are retained in their position by a cross-piece, D, bolted to N by screw-bolt m, and also two eyebolts constructed like Fig. 3. (See S and S', Fig. 1.) Through the eyes of these bolts the rods A and B pass, and when the nuts S and S' are turned it draws A and B firmly against D, while at the same time the plates D' and E are screwed firmly to C by the

bolts 4 5. Now, to widen the distance between the plows 2 and 3, the four bolts 4, 5, S, and S' are unscrewed. D' and E are then moved toward the cross-piece D, and the bolts are screwed up as before.

F is an arm with a wheel, G, on its lower end. In the upper end is a semicircular slot, F O, through which a bolt passes, as also through the ends of the handles H I. By raising this bolt in the slot F O the crook ends of the handles may be raised or lowered at pleasure.

Now, the plow-blades are attached to the frame as follows, to wit: Two bolts 7 8 pass through them, and also through a flat bar of iron, 9, Fig. 2, while the crooked end of the frame-pieces A B C pass between the bar 9 and the plow-blade, and by the screw-bolts are firmly secured to their places. By this arrangement the blades can be easily raised or lowered, turned out or in, as desired. Now unscrew the bolts 4, 5, and m, and remove A, B, and D with the plates D' and E, and I have a shovel-plow alone.

What I claim as my invention, and desire to secure by Letters Patent of the United States, is—

The arrangement of the hooked and double curved central bar, C N, curved slotted arm F, wheel G, handles H I, sliding plates E D', frame-pieces A B, and cross-piece D, substantially as and for the purpose herein shown and described.

MORGAN L. ROGERS.
